UNITED STATES PATENT OFFICE

CHARLES E. BALL, OF CHICAGO, ILLINOIS, ASSIGNOR TO BALL WAGON GRADER CO., OF STOCKTON, CALIFORNIA, A CORPORATION

CONTROL MECHANISM FOR SCRAPER BOWLS

Application filed June 26, 1931. Serial No. 546,985.

This invention relates to scrapers, and particularly to scrapers of that character in which the bowl is suspended in a wheel supported frame, and adapted to be up-ended at its forward end so as to dump from the rear end. The bowl also has a front apron or endgate, normally clear of the bowl when the latter is digging, but mounted so as to contact with and close the front of the bowl when the latter has been raised a certain distance. Such an apparatus is shown in Patent No. 1,593,007, dated July 20, 1926; the present invention dealing with the means for controlling the vertical movement of the bowl and the engagement of said endgate therewith.

The particular object of this invention is to so arrange the raising means in connection with the front endgate that when the bowl is raised from its digging position, it will first be pulled into positive engagement with the endgate, and said gate and bowl will then be raised as a unit while being held rigidly together.

The endgate is always held close against the bowl when the latter is raised to a transporting position, so that no dirt will ever be lost by spilling between the bowl and the endgate during transportation, as was the case with the previous structure, in which the endgate was merely held against the dirt by its own weight and that of the dirt engaged thereby, and was otherwise free to move relative to the bond with the vibration and jarring incident to the movement of the apparatus from one point to another.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of a scraper bowl as mounted in connection with the supporting and control mechanism and in a digging po-

sition, the near frame members being removed.

Fig. 2 is a sectional elevation of the bowl showing the same raised to fully engage the endgate. 55

Fig. 3 is a similar view showing the bowl raised to a dumping position.

Fig. 4 is a fragmentary sectional plan of the structure above the bowl, taken on the line 4-4 of Fig. 2. 60

Referring now more particularly to the characters of reference on the drawings, the scraper structure comprises a main frame 1 of suitable character supported by wheels or endless tracks 2. The bowl 3 of the scraper is disposed in the frame rearwardly of the tracks, and is preferably of the form and construction shown in my co-pending application for patent, Serial No. 547,306 filed June 27, 1931. Arranged in connection with the bowl at the front is an endgate comprising a transversely vertically extending plate 4 having rearwardly projecting side wings 5. This plate is curved to conform to the curvature of the forward edges of the sides 75 of the bowl, the side wings fitting therebetween. The rear lower edge of the plate, when the gate is fully engaged with the bowl, abuts against the forward edge of the cross bar 6 which is secured on the bottom plate 80 of the bowl and which supports the forwardly projecting blade 7 therebelow, as shown in Fig. 2.

Rigid with the wings and projecting rearwardly therefrom are arms 8 which are pivoted at their rear ends on the sides of the bowl. The endgate is normally suspended from chains 9 or the like which depend from and are secured to the frame, and which prevent the endgate dropping below a certain level without interfering with its upward movement. 85

The bowl is supported from the frame by substantially horizontal side arms 10. These arms are pivoted at their rear ends on brackets 11 secured to the outside of the bowl intermediate its front and rear ends and toward the bottom, and at their forward ends on the frame ahead of the bowl. Suspension arms 12 depend from pivotal connections with the 90

frame above the bowl to similar connections with the sides of the bowl at its rear end and near the bottom, said arms normally having a forward slope toward their upper end.

5   Mounted on the frame above the points of connection of the arms 12 therewith are transversely spaced drums 13, which are rotated at the option of the operator by any suitable mechanism which forms no part of 10 this invention. Cables 14 are wound on and depend from these drums, passing between the arms 10 and the sides of the bowl and about guarded sheaves 15 mounted on the bowl ahead of the brackets 11. The cables 15 after passing about the sheaves extend upwardly to fixed connections with the forward face of the endgate plate 4 intermediate its top and bottom, and preferably at points close to the points of connection of the chains 20 9 therewith. While I have described the structure as having a pair of cables, in practice I preferably only use one such cable, this cable passing unbroken from one drum to and about its sheave, up to the endgate and 25 then across the forward face of the endgate from side to side and thence to the other sheave and drum. This cable is held from slipping relative to the endgate by passing about grooved cradles 16 disposed at the corners of the endgate, as shown in Fig. 4.

By reason of this arrangement it will be seen that when the chains 9 are taut, and the endgate is in its normal suspended position, said chains and cable together serve as the 35 means to hold the bowl in a definite position, and paying out of the cable on the drums will cause the bowl to be lowered without affecting the level of the endgate. When the cable is wound on its drum to raise the bowl from 40 its digging position, the front end of the bowl will be raised toward the endgate, while at the same time said gate will be positively held at its limit of downward movement by the pull of the cable. As the bowl is thus 45 raised, the endgate gradually assumes its proper and predetermined bowl engaging position, on account of the pivoted arms 8 which confine the movement of the endgate to a definite arc relative to the bowl. With 50 this relative movement between the front of the bowl and the endgate, the lower edge of the latter cuts through any dirt in its path and positively confines the dirt rearwardly of the same in the bowl.

55   After the lower edge of the endgate engages the cross bar 6, it can of course move no further down. With any further upward movement of the bowl therefore, the ends of the cable anchored on the endgate cause the 60 bowl and endgate to be raised as a unit, and the chains 9 become slack. In other words, as far as the raising of the bowl is concerned, said cable ends could then be anchored on the bowl itself. By having them connected to 65 the endgate instead however, not only are

the endgate and bowl positively brought into engagement with each other, but they are held engaged with equal pressure with any further raising of the bowl. Since the weight of the bowl tends to cause the same 70 to drop at its front end, the endgate and bowl are always maintained in this close and positive engagement with each other when the bowl is raised to its transporting position and the drums are held against rotation.

75   From the foregoing description it will be readily seen that I have produced such a device as substantially fulfills the objects of the invention as set forth herein.

80   While this specification sets forth in detail the present and preferred construction of the device, still in practice such deviations from such detail may be resorted to as do not form a departure from the spirit of the invention, as defined by the appended claims.

85   Having thus described my invention what I claim as new and useful and desire to secure by Letters Patent is:

90   1. In a scraper, a frame supported from the ground, a bowl, means suspending the bowl in the frame for upward tilting at its front end, a front gate for the bowl, means suspending the gate from the frame so that it hangs above the front end of the bowl when the latter is in a scraping position, and a common means exerting a downward pull on the gate while tilting the bowl upwardly and so as to bring the gate and bowl into positive engagement with each other.

95   2. In a scraper, a frame supported from the ground, a bowl, means suspending the bowl in the frame for upward tilting at its front end, a front gate for the bowl, means suspending the gate from the frame so that it hangs above the front end of the bowl when the latter is in a scraping position, 100 sheaves on the sides of the bowl, cable-sections depending from the frame and extending about the sheaves to connections with the gate, and means applied to the cable-sections to move vertically those portions of said sections which extend between the sheaves and frame.

105   3. A structure as in claim 1, with means pivotally connecting the gate in connection with the bowl for positive movement into and out of place relative to the front end of the bowl.

110   4. A structure as in claim 2, with means pivotally connecting the gate in connection with the bowl for positive movement into and out of place relative to the front end of the bowl; and means to positively limit the downward movement of the gate relative to the bowl.

115   5. In a scraper, a frame supported from the ground, a bowl suspended from the frame for upward tilting movement at its front end, a front gate for the bowl, means normally suspending the gate from the frame in po-

sition above the front of the bowl when the latter is in a scraping position, means between the frame and gate to exert a downward pull on the latter, and means between the bowl and said first named means to tilt the bowl upwardly with such pull.

6. In a scraper, a frame supported from the ground, a bowl suspended from the frame for upward tilting movement at its front end, a front gate for the bowl, means normally suspending the gate from the frame in position above the front of the bowl when the latter is in a scraping position, means between the frame and gate to exert a downward pull on the latter, means between the bowl and said first named means to tilt the bowl upwardly with such pull whereby the bowl will ultimately engage and be held against the gate; the gate suspending means being flexible to cause a continuation of the pull, after the bowl and gate have thus engaged, to raise said bowl and gate as a unit.

7. In a scraper, a frame supported from the ground, a bowl suspended from the frame for upward tilting movement at its front end, a front gate for the bowl, means normally suspending the gate from the frame in position above the front of the bowl when the latter is in a scraping position, and a bowl tilting element, and means connecting said element to the bowl and gate in such relationship that the lower edge of the gate, after the bowl has been tilted a predetermined distance, will engage the cooperating surface of the bowl with a pressure proportionate to the weight of the bowl and its load.

In testimony whereof I affix my signature.

CHARLES E. BALL.
